CLAIM

The ornamental design for a tube squeezer, as shown and described.

DESCRIPTION

FIG. 1 is a perspective view of a tube squeezer showing my new design;

FIG. 2 is a left side elevational view thereof;

FIG. 3 is a front elevational view thereof; the rear elevational view being a mirror image thereof;

FIG. 4 is a right side elevational view thereof;

FIG. 5 is a top plan view thereof, the bottom plan view being a mirror image thereof; and

FIG. 6 is a top plan view thereof, the broken lines indicating a tube are shown for illustrative purposes only.

FIG. 1

FIG. 2

FIG. 3

FIG. 4

FIG. 5

FIG. 6
